UNITED STATES PATENT OFFICE

JOHN H. DOMKEE, OF WEST HAVEN, CONNECTICUT, ASSIGNOR TO THE WIRE NOVELTY MANUFACTURING COMPANY, OF WEST HAVEN, CONNECTICUT, A CORPORATION OF CONNECTICUT

SLIDE BUCKLE

Application filed April 4, 1930. Serial No. 441,670.

This invention relates to slide buckles employed for adjusting the length of straps, webbing, and the like, upon which the buckle is mounted, the adjustment being maintained 5 thereby without penetration into the material, and the objects of the invention are to provide an entirely rigid and indestructible slide buckle; to provide a slide buckle that is reversible; to provide a slide buckle of integral outer and inner frames of which the 10 sides lie in a common plane and of which the inner frame provides angularly bent bars relatively spaced and extending across the frames in spaced relation to parallel bars of the outer frame; and to provide such an 15 inner and outer frame structure of which the metal of respective terminals are united in permanent intimate union with engaging metal of the frames. With these and other 20 objects in view as may become apparent from the within disclosures, the invention consists not only of the particular form herein pointed out and illustrated in the drawing, but readily admits of certain modifications 25 within the scope of what may hereinafter be claimed.

The character of the improvement may be best understood by reference to one illustrative device embodying the invention and 30 illustrated by the drawing in which the Figure 1 is an elevation of the buckle of which a reversed elevation would be identical; the Figure 2 is a top view thereof; and the Figure 3 is a perspective view, the Figure 4 being 35 an elevation of a modified structure.

Referring more particularly to the drawing the buckle is made from a single piece of wire of which a middle portion is bent to form an outer rectangular frame having the 40 upper bar 1 and the lower bar 2 integrally connected by the side bar 3, the opposite side of the outer frame being formed by the engaging looped structure terminals 4 and 5 provided by bending each wire portion 45 within the frame and back upon itself, the remaining wire portions being bent in planes parallel to those of the upper and lower bars 1 and 2, respectively, to provide the bars 6 and 7 of the inner frame, the parts 6 and 7 being further bent, in the formation of the

bars, emerge from the plane of the outer frame in one direction and angularly bent to cross and emerge from said plane of the outer frame in the opposite direction, and then angularly rebent to recross said plane 55 of the outer frame, repeatedly, to thus extend relatively spaced from one side of the frame to the other side thereof, the wire terminals 8 and 9 being bent into relative longitudinal alignment within the frame adjacent the 60 side bar 3 to complete the inner frame of which the bent bars 6 and 7 provide spaced peaked humps 10 projecting out of the plane of the buckle in one direction and spaced peaked humps 11 projecting out of the plane 65 of the buckle in the opposite direction. The looped terminals 4 and 5 and the aligned wire terminals 8 and 9, respectively, are united in permanent intimate union by means of welding, brazing, or soldering, as 70 at 12 and 12'. The structure above described and illustrated by the Figures 1, 2, and 3, differs from the structure described and illustrated by the same applicant in an application filed December 13, 1929, Serial Number 75 413,863, in that there is there disclosed a slide buckle comprising a pair of loops in a common plane and having bent intermediate bars in relatively close association and providing the spaced peaked humps extending in 80 opposite directions out of the buckle plane, while the present application discloses a structure of inner and outer frames arranged within a common plane, the relatively spaced bent bars of the inner frame providing the 85 spaced peaked humps extending in opposite directions out of the buckle plane. The relatively spaced and bent bars 6 and 7 may be of more or less distance apart, but their spaced relation to the parallel bars 1 and 2, 90 respectively, approximately as illustrated, is better adapted to off-set a strap, (not illustrated) intended to be threaded into the buckle in the usual manner, than if the bars 6 and 7 were relatively spaced, for instance, 95 a thirty-second of an inch apart. The buckle is reversible in use in that the reversed elevation to that illustrated is identical therewith.

The structure illustrated by the Figure 4 100

is slightly modified in that, while outer and inner frames are provided in a common plane by bending a single length of wire, yet they are formed by doubling the wire and then bending the doubled wire in its own plane to assume substantially rectangular forms, one within the other, providing the relatively spaced parallel bars 1A and 6A, the relatively spaced parallel bars 2A and 7A, and the closely associated side bars 4A and 5A of one side of the frames and the wire terminals 3A and 9A forming the other side, the relatively spaced bars 6A and 7A of the inner frame being bent as in the preferred form to provide the spaced peaked humps 10A and 11A. The extremities of the wire terminals 3A and 9A being united in permanent intimate union with engaging portions of the frames, as at 12B, the meeting metal surfaces of the bars 4A and 5A being also relatively united in the same manner, as at 12A.

extend relatively spaced and in spaced relation to the upper and lower bars, respectively, to the integrally connecting side bar, the wire extremities being bent into alignment, one with the other, within the frame, and the engaging metal of the extremities and the engaging metal of the side portions being united, respectively, in permanent intimate union to provide a rigid structure.

JOHN H. DOMKEE.

75

I claim:—

1. A slide buckle comprising a piece of wire of which a middle portion is bent to form a rectangular frame having upper and lower parallel bars, other integral portions of the wire being bent to provide intermediate bars relatively spaced and parallelly spaced from the upper and lower bars, respectively, each of the intermediate bars being bent to emerge from the plane of the frame in one direction and angularly bent to cross and emerge from said plane in the opposite direction and then rebent to recross said plane, repeatedly, the metal of the structural and wire terminals being united in permanent intimate union with the engaging metal of the frame to provide a rigid structure.

2. A slide buckle comprising a piece of wire bent to integrally form outer and inner frames having opposite sides lying in a common plane and having relatively spaced upper and lower bars of which the bars of the inner frame are bent out of said plane in one direction and angularly rebent to cross and emerge from said plane in the opposite direction and then angularly rebent to recross said plane, repeatedly, to thus extend relatively spaced from one side of the frames to the opposite side thereof, and the metal engaging structural and wire terminals being united in permanent intimate union with the frames.

3. A slide buckle comprising a piece of wire of which a middle portion is bent to form a rectangular frame having upper and lower bars integrally connected by a side bar, portions of the wire aligned, one with the other, cooperating to form the opposite side of the frame, each aligned portion being bent back upon itself within the frame, and the remaining wire portions being bent to emerge out of the plane of the frame in one direction and angularly bent to cross and emerge from said plane in the opposite direction and then rebent to recross said plane, repeatedly, to
